UNITED STATES PATENT OFFICE.

ALBERT S. BLATTERMAN, OF NORTH ASBURY PARK, NEW JERSEY, ASSIGNOR TO B. M. C. PATENT COMPANY, OF TRENTON, NEW JERSEY, A CORPORATION OF NEW YORK.

METHOD OF AND MEANS FOR OPERATING A TUNED RADIO RECEIVER.

Application filed May 21, 1925, Serial No. 31,801. Renewed December 3, 1928.

My invention relates to radio receivers and more particularly to those of the tuned radio frequency amplification type in which it is desired to accomplish the entire range of tuning of the receiver by means of a single control member such as a rotatable dial. This control would, for example, include the simultaneous tuning of the input circuit of the receiver, of one or more stages of radio frequency amplification and of the detector stage.

Up to the present it has been substantially impossible to secure simultaneous and equal tuning of these several circuits by means of a single control element for reasons which will be pointed out hereafter.

In the drawings accompanying my specification I show in:

Figure 1 a diagrammatic representation of a receiver having one stage of tuned radio frequency amplification; and in

Figure 2 a curve indicating the relation between antenna capacity and wave length, which will be referred to in my description.

It will be understood that my invention is applicable to a wide variation of uses and that I do not intend to limit myself to the particular embodiment illustrated in the drawings. Specifically, it will be understood that my invention is particularly useful where a multi-stage radio frequency amplifier is used.

Referring to Figure 1, 1 represents the antenna connected to ground at 2, variable connections to the primary 4 of the antenna tuning inductance being made possible through the switch 3. The antenna system is inductively coupled to the secondary 5 included in the input circuit of the first stage of radio frequency amplification; this stage including the tuning condenser 6, the vacuum tube 7, the usual B battery 8 and filament battery 9. This stage may be coupled to another stage of amplification or to a detector stage by means of a coupling transformer 10, 11 which stage contains the usual tuning capacity 12 and the other instrumentalities ordinarily used.

In the arrangement in use at the present time, the inductances 4 and 5 and 10 and 11 are fixed and the capacities 6 and 12 are so connected as to be operated by a common operating member 15 having a dial 16. In such an arrangement even if the inductances and

tuning condensers in the several stages are made to have identical values at all settings, 55 the system will not operate satisfactorily for the following reasons. It will be seen that the capacity of the antenna circuit is reflected into the first stage of radio frequency amplification and that the capacity of the tube 7 is 60 reflected into the next succeeding detector or amplifier stage. The capacity of the antenna circuit is a capacity of an entirely different order from the capacity of the tubes, and for this reason the transformer-condenser circuit 65 associated with the antenna will tune in an entirely different manner from the transformer-condenser circuit associated with an amplifier stage, thus merely simultaneously varying the capacities and will not produce 70 the desired result because the difference in the reflected capacities will be felt in the several stages and will cause mistuning as a consequence.

If C_1 represents the capacity in the primary 75 circuit of a transformer of the type under discussion, L_1 represents the inductance in the primary circuit of such a transformer and C_2 represents the tuning capacity across the secondary winding of such a transformer, it 80 can be shown that the effect of the presence of the primary circuit when tightly coupled to the secondary circuit is to introduce into the secondary circuit from the primary circuit an effective capacity approximately equal to 85

$$\frac{L_1 C_1}{L_2}$$

The effective capacity thus introduced into the secondary circuit I have termed "reflected 90 capacity". In this type of circuit it is well known that the secondary current is maximum, that is, the best tuning effect is obtained when the reactance of the secondary bears to the reactance of the primary the same 95 ratio that the square of the mutual reactance between the two circuits bears to the square of the primary impedance. This relationship is expressed in formula 36, page 163, of "Electric Oscillations and Electric Waves" 100 by Pierce, published by McGraw-Hill & Company. If X_1 represents the reactance of the primary circuit, X_2 the reactance of the secondary circuit, M the mutual inductance between the primary and secondary circuits, 105 and Z_1 the impedance of the primary circuit,

this relationship may be expressed mathematically by the following equation:

$$(1) \quad \frac{X_2}{X_1} = \frac{\omega^2 M^2}{Z_1^2}$$

5 The resistance of the primary circuit may be considered as negligible in comparison with its reactance, hence Z_1 is approximately equal to X_1 and the above formula becomes after 10 transposition:

$$(2) \quad X_2 = \frac{\omega^2 M^2}{X_1},$$

or

$$15 \quad (3) \quad \omega L_2 - \frac{1}{\omega C_2} = \frac{\omega^2 M^2}{\omega L_1 - \frac{1}{\omega C_1}}$$

For tight coupling between the primary and the secondary circuit as is customary in the practical use of circuits of this type, M is approximately equal to $L_1 L_2$. Therefore, (3) becomes

$$25 \quad (4) \quad \omega L_2 - \frac{1}{\omega C_2} = \frac{\omega^2 L_1 L_2 C_1}{\omega^2 L_1 C_1 - 1}$$

In practice the resonant frequency of the primary circuit is considerably below the frequencies that are being used in reception, hence $\omega^2 L_1 C_1$ may be neglected in comparison 30 with unity and (4) becomes

$$(5) \quad \omega^2 L_2 C_2 - 1 = \omega^2 L_1 C_1 L_2 C_2$$

When the secondary elements L_2 and C_2 are properly tuned, the quantity $\omega^2 L_2 C_2$ would 35 exactly equal unity were it not for the presence of the primary circuit. As a close approximation we may, therefore, consider $\omega^2 L_2 C_2 = 1$. Hence (5) becomes

$$40 \quad (6) \quad \omega^2 L_2 C_2 - 1 = \omega^2 L_1 C_1,$$

or

$$(7) \quad \omega^2 L_2 \left(C_2 + \frac{L_1 C_1}{L_2} \right) - 1 = 0$$

45 From Equation (7) it is at once apparent that the effective secondary capacity is greater than the actual capacity C_2 by the amount

$$\frac{L_1 C_1}{L_2}.$$

50 This additional capacity appears because of the fact that the secondary circuit is not isolated but is coupled to the primary circuit, which, because of this coupling, reflects to the secondary circuit a capacity equal to the value 55 calculated, namely

$$\frac{L_1 C_1}{L_2}.$$

60 It will be noted that several approximations have been made in the derivation of the foregoing formula so that the result is only an approximate expression, as above stated, but in practice I have found this expression to be sufficiently exact for design purposes.

65 In the case of a transformer directly as-

sociated with the antenna circuit, the value of C_1 is the capacity of the antenna against the ground which ordinarily may be of the order of several hundred micro-micro-farads. The case of the subsequent transformers in 70 the amplifier stages, the value of C_1 is the effective capacity of the vacuum tubes connected to the primary windings of the transformers and this has a value of the order of 10 micro-micro-farads. It is evident, therefore, that if the secondary tuning capacities C_2 in the several stages are identical and the primary inductances L_1 are identical, that the antenna stage will not tune in the same way as the amplifier stages on account of the 80 fact that C_1 in the antenna stage is many times larger than C_1 in the amplifier stages.

I have discovered that I can compensate for this difference in the reflected capacities by introducing into the amplifier stages a capacity 85 13 connected between the plate and filament electrodes of the vacuum tube; that is to say, in the same relative position in respect to the primary 10 of the coupling transformer as the capacity of the antenna is with 90 respect to the primary 4 of the antenna transformer.

If more than one stage of radio frequency amplification is used, condensers similar to condenser 13 are connected in corresponding 95 locations in each of the stages. The capacities 13 are preferably fixed condensers and have a value substantially equal to the value of the antenna capacity, for the reason that, at a given appropriate wave length, they reflect into the next succeeding stage a capacity 100 equal to the capacity reflected by the antenna into the first stage.

The arrangement just described would permit of simultaneous tuning by adjustment of 105 condensers 6 and 12 to the same degree and mechanically connecting them to operate together, were it not for the fact that, as is well recognized the effective capacity of the antenna varies with the wave length. In Figure 2 I have shown a curve expressing the relation between effective antenna capacity and wave length, from which it will be seen that the effective antenna capacity varies very

110 greatly at short wave lengths and is substantially constant and has relatively lower values at long wave lengths. A consideration of this curve will make it evident that fixed compensation, as obtained by the inclusion of condensers such as 13, would be ineffective 115 if the receiver is intended to operate over a relatively wide band of wave lengths and that under such conditions fixed compensation is impractical, it being necessary to introduce additional compensation to take care of variations in effective antenna capacity due to 120 variations in wave length. I have found that this additional compensation may be introduced by varying the primary inductance of the antenna circuit so as to change the capac- 130

ity reflected from the antenna circuit into the tuned secondary circuit; that is, the first amplifier stage.

As stated above, the reflected capacity in 5 the first amplifier stage is expressed by the quantity

$$\frac{L_1 C_1}{L_2}$$

10 and it will be evident from this quantity that its value may be increased or decreased by increasing or decreasing the factor L_1 of the numerator. In the particular example described above, this may be accomplished by 15 moving the switch 3 over a series of taps as shown on the coil 4 or by otherwise varying the inductance of the antenna circuit. It will also be seen that the value of this expression might be changed by varying the 20 effective capacity of the antenna circuit (that is, the factor C_1) by introducing additional capacity in series with the antenna; such additional capacity being illustrated by the dotted condenser 14.

25 The particular mechanical means by which the condensers 6 and 12 and the switch 3 (or the condenser 14) may be simultaneously operated is shown conventionally by the dotted lines 15 and 16.

30 In the operation described it will be understood that the compensating capacity 13 is chosen of such a value as to compensate for the smallest reflected capacity due to the antenna which might be experienced in the normal operation of the device; that is to say, the reflected capacity appropriate to the longest wave length the receiver is adapted to receive. For shorter wave lengths the reflected capacity is decreased by decreasing the 35 inductance or capacity of the antenna circuit, as stated above. That is to say, decreasing the factors L_1 or C_1 or both. When decreasing the product $L_1 C_1$ of the antenna circuit for shorter wave lengths, either by decreasing 40 the capacity or inductance of the antenna circuit, there results a looser coupling of the antenna with the first amplifier stage, a desirable result in an apparatus of this character and which produces an increase in signal 45 strength, it being generally recognized that looser couplings for shorter wave lengths and tighter couplings for longer wave lengths give a more uniform transfer of the received signals throughout the wave length band to 50 which the receiver may be tuned.

55 While I have described my invention in one of its preferred forms, there are many possible changes and variations and these I desire to include within the scope of my 60 claims.

I claim:

1. In a vacuum tube radio receiver including at least one stage of tuned frequency amplification and a tuned detector stage, the 65 combination with tuning means in each stage

mechanically connected together for simultaneous operation, of means for providing a fixed compensation in each stage after the first for the capacity reflected from the antenna circuit into the input circuit of the 70 first stage at a given wave length, and means in the antenna circuit adapted to be adjusted by operation of said tuning means for maintaining said reflected capacity substantially constant regardless of variations of wave 75 length from said given wave length.

2. In a vacuum tube radio receiver including at least one stage of tuned radio frequency amplification and a tuned detector stage, the combination with coupling transformers between the antenna and the first stage and between the successive stages, and tuning means in each stage mechanically connected together for simultaneous operation, of means for providing a fixed compensation in each 80 stage after the first for the capacity reflected from the antenna circuit into the input circuit of the first stage at a given wave length, and means in the antenna circuit operable by manipulation of said tuning means for maintaining said reflected capacity substantially constant regardless of variations of wave 85 length from said given wave length.

3. In a vacuum tube radio receiver including at least one stage of tuned radio frequency amplification and a tuned detector stage, the combination with coupling transformers between the antenna and the first stage and between the successive stages, and tuning means associated with the secondary 90 of each transformer mechanically connected together for simultaneous operation, of means associated with the primary of each transformer after the first for providing a fixed compensation for the capacity reflected 95 from the antenna circuit into the secondary of the first transformer at a given wave length, and means in the antenna circuit operable by manipulation of said tuning means for maintaining said reflected capacity substantially constant regardless of variations of wave 100 length from said given wave length.

4. In a vacuum tube radio receiver including at least one stage of tuned radio frequency amplification and a tuned detector stage, the 115 combination with similar coupling transformers between the antenna and the first stage and between the successive stages, and similar tuning condensers shunted across the secondary of each transformer mechanically 120 connected together for simultaneous operation, of fixed condensers connected across the primary of each transformer after the first, the capacity of each fixed condenser being substantially equal to the effective capacity 125 of the antenna circuit at the longest wave length the set is adapted to receive, and means operable by manipulation of said tuning condensers for maintaining the effective capacity 130 introduced into the secondary of the first

transformer by the antenna circuit coupled thereto substantially constant.

5. The method of operating vacuum tube radio receivers comprising at least one stage of tuned radio frequency amplification and a tuned detector stage, each stage having similar tuning elements adapted to be operated simultaneously by a common control, which comprises compensating in each stage after 10 the first for the capacity reflected into the first stage from the antenna circuit at a given

wave length, and varying the impedance of the antenna circuit automatically with adjustment of the tuning control to maintain said reflected capacity substantially constant 15 regardless of variations of wave length from said given wave length.

In testimony whereof, I have signed my name to this specification this 19th day of May, 1925.

ALBERT S. BLATTERMAN.
